UNITED STATES PATENT OFFICE.

ALFRED BONOM, OF MONDOVI, ITALY.

TURBINE.

Application filed June 17, 1927, Serial No. 199,595, and in Italy March 22, 1927.

This invention relates to radial turbines with two rotors turning in opposite directions and has for its object an improved machine which is exceptionally compact owing to a rational arrangement of its parts, as well as simple in construction and assembly and of a high thermic efficiency.

According to this invention the turbine generally comprises at least two stages, a high-pressure and a low-pressure stage, respectively, arranged concentrically so as to deliver the pressure fluid directly from the high-pressure stage to the low-pressure stage, thus eliminating the long connecting pipes required in the other types of turbines.

Preferably each stage is subdivided into a plurality of sections placed side by side and fed in parallel, so as to reduce the diameter of the turbine and keep the centrifugal force within the limits allowed by the material employed, giving at the same time a more compact machine. Preferably the low-pressure stage comprises a number of sections which is a multiple of the number of sections of the high-pressure stage and the arrangement of the sections is such as to deliver the pressure fluid without any considerable loss in flowing from one stage to the next. In the case of higher power turbines, according to this invention a middle-pressure stage is used comprising one or a plurality of sections which are conveniently placed between the high-pressure stages so as not to increase in the least the outer diameter of the turbine.

By the peculiar arrangement and subdivision of the stages it is possible to obtain the rotor blade carriers as members of easy manufacture that are connected together by successive axial keying making the construction exceptionally cheap.

A further important feature of this invention consists in that the distribution of the stages allows a perfect automatic balancing of the rotating members to be obtained, as well as of arranging in conveniently chosen points compensating chambers, when it is necessary to eliminate or reduce the axial thrust exerted by the pressure fluid in opposite directions on the members of the outer rotor.

When the power of the turbine does not exceed a certain limit, the inner and outer rotors can be connected together at one end by a differential gearing and can be pro-

vided at their other end with a clutch mechanism for selectively connecting them to a propeller shaft, movement being reversible as described in another application in the same name. When, however, the power exceeds an allowable limit with respect to the resistance of the differential gearing, the two rotors are maintained independent of each other and can be connected with two consumption machines having the same power and speed features or inversely proportional features, i. e. electric generating machines. This latter arrangement shows a characteristic coupling of the shaft of the outside rotor with the shaft of the consumption machine, which allows an efficient ventilation of the coupling itself, so as to prevent transmission of heat from the turbine to the consumption machine; of course a similar arrangement can be adopted also for the shaft of the inner rotor, and in this case the coupling shall be separate and fixed on said shaft owing to obvious assembly grounds.

Further features of my invention shall be set forth in the appended specification referring more specifically to the drawings, wherein:

Figure 1 is a longitudinal axial section of the upper half of a reversible turbine with two stages and of middle power;

Figure 2 is a similar section showing a turbine with independent rotors comprising two stages subdivided into two and six sections, respectively;

Figure 3 is a detailed view thereof and Figures 4 and 5 show in sectional views similar to those of Figures 1 and 2, respectively, a reversible turbine and a turbine with independent rotors comprising three stages subdivided into sections.

Referring to Figure 1, 1 denotes the main shaft, on which is keyed the inner rotor consisting of the hub 2 resting against the shoulder 3 of the shaft 1 and of the rotor blade carrier comprising a central part 4 for high pressure, an intermediate connecting part 5 provided with holes 6 for the flow of the pressure fluid and a peripheral portion adapted to carry the blades of one of the sections of the low-pressure stage, which, in the example shown is subdivided into two sections B_1 and B_2 , respectively. The rotor blade carrier of the other section B_2 consists of an annular disc mounted in a hot condi-

tion on annular projections 9 of the portion 7.

The outside rotor consists of a sleeve 10, a carrier comprising a central portion 11 carrying the blades of the high-pressure stage, an intermediate connecting part 12 and a peripheral part 13 adapted to carry the blades of the section B_1 and a disc, the peripheral portion 14 whereof carries the blades of the section B_2 , while its central portion 15 forms together with the rotor blade carrier 4 a balancing chamber divided by a labyrinth 16 into a lower compartment 17 communicating through holes 18 directly with the admission pipe 19 for the pressure fluid and an upper compartment 20 communicating with the exhaust chamber of the high-pressure stage and at the same time with the admission chamber for the low-pressure stage.

Rods 21 placed at regular intervals on the periphery of the pieces 13 and 14 connect in due spaced relation the lateral carriers 11 and 15 and the central ring 22 fixed to the ends of the circular series of outer blades 23 of the sections B_1 and B_2 . Said rods, preferably of rhomboid section, extend through holes on the periphery of the portions 13 and 14 of the ring 22 and said portions are maintained exactly spaced by a tenon and notch and lock key connection between them and the rods; for this purpose these latter are provided with notches 24 engaging the edges of the holes through which the rods extend, said rods being held in position by keys 25 inserted between the rods and the opposite hole wall.

The sleeve 10 carries a circular series of openings 26 establishing communication between the admission pipe 19 and the connecting pipe 27 fast with the stationary casting 28 of the turbine.

Labyrinth packings are arranged in suitable points of the machine, e. g. the packings 29-30 and 31 between the stationary part and the outside rotor and the packings 32 between the hub of the inner rotor and the sleeve-shaft 10 of the outside rotor.

The turbine is of the reversible type, the rotors are therefore connected together at one end in the known manner by means of the differential gearing 33 (of which the drawing only shows a sector) and carry at their other end the fixed members 34 and 35, respectively, of a dog clutch, the slideable element whereof is fast in rotation with the propeller shaft 37.

Figure 2 shows a turbine with two stages, wherein the high-pressure stage is subdivided into two parallel sections and the low-pressure stage is subdivided into six parallel sections concentrical to the former. Owing to the high power of this turbine the rotors are made independent and in this case the turbine is adapted to drive two op-

erating machines having the same power and speed features. The connection between the shaft 40 of the outside rotor and the shaft 41 of the operating machine (not illustrated) is effected by means of a special coupling shown in detail in Figure 3. This joint comprises two cups 42 integral or secured in any suitable way to the shafts 40, 41 and provided with connecting flanges 43. The cups prevent the transmission of heat from the turbine to the operating machine and for this purpose they are formed on their walls with holes 44 conveniently inclined with respect to the axis of the shaft so as to generate by the rotation of this latter a strong circulation of air within the cups.

The inner rotor of this turbine comprises for the sections A_1 and A_2 of the high-pressure stage a couple of central rotor blade carriers 45 placed in contact with each other with the interposition of suitable packing rings 46 lodged in circular grooves formed on the contacting surfaces. Cylindrical bodies or drums 47 extend from the edge of these carriers to the outside concentrically to the turbine axis, and at the ends of said drums 47 are situated the rotor blade carriers of the sections B_1 , B_2 and B_5 , B_6 of the low-pressure stage. Each of these rotor blade carriers consists of an element 48 fast with the drum 47 and of an annular element 49 which is mounted in a hot condition on annular projections 50 of the member 48. A slightly different arrangement is provided in the central part, wherein the rotor blade carrier of the stages B_3 - B_4 comprises elements 51 and 52 connected together in a hot condition similarly to the elements 48 and 49 and directly lodged on the ring 53 of the central carriers. For fixing purposes the element 52 is formed with an annular rib 54 which fits between the carriers 45 and engages a plurality of pins 55 that hold it against rotation. The longitudinal section of the inner rotor thus formed has the characteristic shape of a candlestick with three arms.

The outside rotor comprises the rotor blade carriers 55, 55' of the sections A_1 and A_2 of the high-pressure stage, the cylindrical bodies 56-56' extending to the outside from the edge of said carriers and the rotor blade carriers 57-57' of the end sections B_1 - B_2 of the low-pressure stage. The rotor blade carriers 57-57' are connected together by means of rods 58 regularly spaced on the periphery and supporting the rings 59 surrounding the rotor blade carriers of the low-pressure stage of the inner rotor and the rotor blade carriers of the stages B_2 - B_3 and B_4 - B_5 , consisting of two elements connected together in the manner already set forth.

Between the turbine casing 60 and the

rotor blade carriers of the high-pressure stage are provided compensating chambers 61 as described with reference to Figure 1. In this case, however, in order to have a 5 prompt balance when starting the turbines, said compensating chambers are reduced in volume by placing therein filling rings 62 secured to the casing.

As in the foregoing construction labyrinth packings 63 are placed in the points in 10 relative motion along the path of the pressure fluid in order to ensure a tight joint and the rotor blade carriers are formed with connecting holes 64 so that the pressure fluid may flow easily to the various sections 15 of the high-pressure and low-pressure stages and to the balancing chambers.

The same principles followed in the constructions of two-stage turbines illustrated 20 in Figures 1 to 3 are employed in connection with three-stage turbines. Figure 4 shows in longitudinal axial section a reversible three-stage turbine, wherein the inner rotor comprises a couple of central carriers 70, of 25 which the hubs 71 are directly keyed on the main shaft 72. The said carriers are arranged in contact with each other and carry on their outer faces the blades of the sections M_1 — M_2 of the intermediate pressure stage. 30 In the central portion of the carriers 70 are provided the tubular bodies 73 ending with the rotor blade carriers 74 for the sections A_1 and A_2 of the high-pressure stage and provided with hubs 75 tightly surrounding 35 the hubs 71 of the carriers 70. Frustum-shaped bodies 75 extend laterally from the periphery of the carriers 70 and carry on their base in the manner of flanges the rotor blade carriers 77 for the blades of the sections B_1 — B_2 and B_3 — B_4 , respectively, of 40 the low-pressure stage. These carriers comprise two elements connected together by keying in a hot state and forming a hollow triangular section as described with reference to Figures 1 and 2.

The outside rotor comprises the carriers 79 and 78 of the sections A_1 and A_2 of the high-pressure stage, to the edges whereof are secured the tubular flared bodies 80 carrying in their annular central portion the blades of the sections M_1 — M_2 of the intermediate-pressure stage and in the peripheral portion of the blades of the sections B_1 and B_4 of the low-pressure stage. The tubular bodies 80 are connected together peripherally by rods 81 supporting the carrier 82 carrying the blades of the low-pressure sections B_2 — B_3 and the rings 83 surrounding the carriers 77. As in the construction according to Figure 1, the shaft 72 is connected at one end with the sleeve 84 fast with the rotor blade carrier 78 through the differential gearing 85 shown partially in the drawing. At its opposite end and by 65 means of the clutch 86 the shaft 72 or the

sleeve 87 fast with the rotor blade carrier 79 can be connected with the driven shaft 88. The pressure fluid is admitted through the admission pipe 89, and flows into the longitudinal pipe 90, by which it is delivered to 70 the sections A_1 and A_2 of the high-pressure stage; whence it flows back towards the axis between the rotor blade carriers 74 and 80, and passes through the sections M_1 — M_2 of 75 the intermediate-pressure stage by which it is directly supplied to the four sections of the low-pressure stage. In this case the rotor blade carriers of each stage are interbalanced and the balancing chambers are thus dispensed with.

Figure 5 shows a very high-power turbine including three stages, wherein the high-pressure stage comprises two sections A_1 — A_2 supplied through independent lateral feed pipes 100, the middle-pressure stage comprises four sections M_1 , M_2 , M_3 and M_4 arranged between the sections A_1 and A_2 , and the low-pressure stage comprises eight sections B_1 , B_2 . . . . B_8 arranged concentrically around the middle-pressure and high-pressure stages. To the shaft 101 is keyed the inner rotor comprising the rotor blade carriers 102, 102' and 103, 103' coupled two by two and carrying the blades of the intermediate pressure sections M_1 , M_2 and M_3 , M_4 , respectively. The rotor blade carriers 102 and 102' extend radially with the interposition of thin flanges 106 so as to form tubular bodies 104—104' carrying at their ends 90 the rotor blade carriers 105—105' of the sections B_1 , B_2 and B_7 , B_8 , respectively, of the low-pressure stage. Similarly the rotor blade carriers 103 and 103' extend radially with the interposition of a thin flange 107 and carry the annular rotor blade carriers 108—108' of the sections B_3 , B_4 and B_5 , B_6 of the low-pressure stage. Laterally of the pairs of carriers 102—103 and 102'—103' are keyed to the shaft 101 the rotor blade carriers 109, 109' of the sections A_1 , A_2 of 100 the high-pressure stage. The outside rotor comprises the rotor blade carriers 110—110' of the high-pressure sections A_1 , A_2 and their relative sleeve-shafts 111—111', the conical tubular bodies 112—112' connected to the 115 rotor blade carriers 110—110' by thin flanges 113 and carrying internally the rotor blade carriers 114—114' of the sections M_1 , M_4 of the middle-pressure stage and externally the rotor blade carriers 115—115' of the low-pressure sections B_1 and B_8 .

The rotor blade carriers 115—115' are connected together by the rods 116 centrally supported by the rotor blade carrier 117 loosely mounted on the hubs of the rotor blade carriers 103—103' and carrying the blades of the sections M_2 , M_3 of the middle stage and of the sections B_4 , B_5 of the low-pressure stage. The rods 116 support in 120 their turn the rotor blade carriers 118—118'

of the sections B_2 , B_3 and B_6 , B_7 and the rings 119—119' surrounding the rotor blade carriers 105—105'.

The rotor blade carrier 117 divides the 5 turbine into two symmetrical parts separately traversed by two streams of pressure fluid that is discharged into a common casing 120.

The thin flanges provided in the intermediate zones between the high-pressure elements and the low-pressure elements have the very important object to make the parts self-adjustable under the action of the centrifugal force by their flexibility. The restrained section of these flanges offers moreover an efficient resistance to the transmission of heat.

It is obvious that such zones of restrained section or zones of flexibility are provided 20 in all those points where they are required by particular working and temperature conditions; examples of such zones of flexibility are also shown by 121 in Fig. 1.

It will be understood from what has been 25 described above that the examples illustrated are all based on the same principle of dividing the stages into a plurality of sections placed side by side according to the turbine power and of arranging and generally forming 30 the said sections in a similar manner in the various types of turbines; while leaving this principle unaltered the said turbines can be modified without departing from the spirit of this invention as set forth in the 35 appended claims.

What I claim is:

1. In a radial turbine a main shaft, an inner rotor mounted on said main shaft and comprising a rotor blade carrier having a 40 central series of blades for the high-pressure stage on one face and a peripheral series of blades concentrical to the former on each face for the low-pressure stage, the series of blades for the low-pressure stage being divided from the series of blades of the high-pressure stage by an intermediate portion of the rotor blade carrier provided with openings and a thin annular flexible flange, a hollow shaft mounted concentrically around 45 the main shaft, an outside rotor keyed on said hollow shaft and comprising a couple of rotor blade carriers placed laterally of the rotor blade carrier of the inner rotor, a central series of blades mounted on one face of 50 one of said rotor blade carriers for co-operating with the central series of blades of the inner rotor, a peripheral series of blades on a face of each of said rotor blade carriers for co-operating with the peripheral series 55 of blades of the inner rotor and an intermediate portion of the rotor blade carrier between the series of blades of the high-pressure and low-pressure stages having a thin annular flexible flange.

2. In a radial turbine, a casing, a main

shaft, an inner rotor mounted on said shaft and comprising a rotor blade carrier having a central series of blades for the high-pressure stage on one face and a peripheral series of blades concentrical to the former on each face for the low-pressure stage, an intermediate portion of the rotor blade carrier between the high-pressure and low-pressure stage, said portion being of restrained section in order to be flexible, a hollow shaft 70 mounted concentrically around the main shaft, an outside rotor keyed on said hollow shaft and comprising rotor blade carriers arranged laterally of the rotor blade carrier of the inner rotor, a central series of blades 75 mounted on a face of each of said rotor blade carriers for co-operating with the blades of the high-pressure stage of the inner rotor, a peripheral series of blades on a face of each of said rotor blade carriers for co-operating 80 with the blades of the low-pressure stage of the inner rotor, an intermediate portion of one of the outer rotor blade carriers between the high-pressure and low-pressure stages, said portion being of restrained section in 85 order to be flexible, and a compensating chamber between the other outer rotor blade carrier and the inner rotor blade carrier, said chamber communicating with the fluid admission annulane and being separated by 90 a labyrinth packing from the exhaust of the high-pressure stage.

3. In a radial turbine, an inner rotor comprising disk-shaped members having a central series of blades for the high-pressure stage and a peripheral series of blades concentrical to the former for the low-pressure stage, an outer rotor comprising disk-shaped members having series of blades co-operating with the series of blades of the high-pressure 100 and low-pressure stages of the inner rotor, the rotor blade carriers of the inner rotor and the rotor blade carriers of the outer rotor being connected together by axial keying.

4. In a radial turbine, a main shaft, an inner rotor mounted on said shaft and comprising rotor blade carriers having a central series of blades for the high-pressure stage and a peripheral series of blades concentrical to the former for the low-pressure stage, a hollow shaft surrounding the main shaft, an outside rotor mounted on said hollow shaft and comprising rotor blade carriers having series of blades co-operating with the series of blades of the high-pressure and low-pressure stages of the inner rotor, a differential mechanism at one end for connecting the hollow shaft with the main shaft, a driven shaft at the other end and a clutch mechanism for selectively connecting said 115 driven shaft with the main shaft and hollow shaft.

5. In a radial turbine a main shaft, an inner rotor mounted on said shaft and comprising disk-shaped rotor blade carriers hav- 120

- ing a central series of blades for the high-pressure stage and a peripheral series of blades concentrical to the former for the low-pressure stage, a hollow shaft mounted 5 concentrically to and turning independently of the main shaft, an outside rotor mounted on said hollow shaft and comprising disk-shaped rotor blade carriers having series of blades co-operating with the series of blades 10 of the high-pressure and low-pressure stages of said inner rotor, a driven shaft and a coupling device between said driven shaft and one of said rotor shafts.
6. In a radial turbine a casing, an inner 15 rotor comprising disk-shaped rotor blade carriers having a central series of blades for the high-pressure stage and a peripheral series of blades concentrical to the former for the low-pressure stage, an outside rotor 20 comprising disk-shaped rotor blade carriers having series of blades co-operating with the series of blades of the high-pressure and low-pressure stages of the inner rotor, compensating chambers between the end carriers 25 of the outer rotor and the casing, openings for establishing communication between said chambers and the admission pipe of the pressure fluid, and labyrinth packing separating said chambers from the exhaust chamber of 30 the turbine.
7. In a radial turbine a casing, an inner rotor comprising disk-shaped rotor blade carriers having a central series of blades for the high-pressure stage and a peripheral 35 series of blades concentrical to the former for the low-pressure stage, an outside rotor comprising disk-shaped rotor blade carriers having series of blades cooperating with the series of blades of the high-pressure and 40 low-pressure stages of the inner rotor, compensating chambers between the end carriers of the outer rotor and the casing, openings for establishing communication between 45 said chambers and the admission pipe of the pressure fluid, labyrinth packings separating 50 said chambers from the exhaust chamber of the turbine and filling rings adapted to reduce the volume of said chambers in order to obtain an instantaneous action of said compensating chambers when starting the turbine.
8. In a radial turbine, an inner rotor comprising disk-shaped rotor blade carriers subdivided at their periphery into a plurality 55 of annular parallel flanges, a central series of blades on each of said carriers forming an element of a section of the high-pressure stage, a series of blades mounted on both faces of the peripheral flanges and forming 60 the elements of the sections of the low-pressure stage, an outside rotor comprising a couple of end carriers, each carrying a central series of blades forming the other element of the section of the high-pressure stage and a peripheral series of blades forming 65 the other element of the end sections of the low-pressure stage, annular intermediate rotor blade carriers carrying the series of blades forming the other element of the intermediate sections of the low-pressure stage and means for rigidly connecting together 70 the end carriers and the annular intermediate carriers in adjusted position.
9. In a radial turbine, an inner rotor comprising disk-shaped rotor blade carriers subdivided at their periphery into a plurality of annular parallel flanges, a central series of blades on each of said carriers forming an element of a section of the high-pressure stage, a series of blades mounted on both faces of the peripheral flanges and forming the elements of the sections of the low-pressure stage, an outside rotor comprising a couple of end carriers, each carrying a central series of blades forming the other element of the sections of the high-pressure stage and a peripheral series of blades forming the other element of the end sections of the low-pressure stage, annular intermediate rotor blade carriers carrying the series of blades forming the other element of the intermediate sections of the low-pressure stage and a plurality of rods regularly spaced on the periphery of said end carriers for connecting together these latter and supporting 80 and holding in position said annular intermediate carriers.
10. In a radial turbine, an inner rotor comprising disk-shaped rotor blade carriers subdivided at their periphery into a plurality of annular parallel flanges, a central series of blades on each of said carriers forming an element of a section of the high-pressure stage, a series of blades mounted on both faces of the peripheral flanges and forming the elements of the sections of the low-pressure stage, an outside rotor comprising a couple of end carriers, each carrying a central series of blades forming the other element of the sections of the high-pressure stage and a peripheral series of blades forming the other element of the end sections of the low-pressure stage, annular intermediate rotor blade carriers carrying the series of blades forming the other element of the intermediate sections of the low-pressure stage, rings closely surrounding the elements of the sections of the low-pressure stage of the inner rotor and means for rigidly connecting together the end carriers, the annular carriers and the intermediate rings.
11. In a radial turbine, an inner rotor comprising disk-shaped rotor blade carriers subdivided at their periphery into a plurality of annular parallel flanges, a central series of blades on each of said carriers forming an element of a section of the high-pressure stage, a series of blades mounted on both faces of the peripheral flanges and 120

- extending inwardly and forming the other element of the sections of the middle-pressure stage and peripheral series of blades carried by each end carrier forming the other element of the end sections of the low-pressure stage, a driven shaft and a coupling device between said driven shaft and one of the rotor shafts in the form of flanged cups connected together to form a chamber, said cups being provided with holes inclined to the axis of rotation in order to improve the circulation of air in said chamber during rotation.
16. In a radial turbine, an inner rotor comprising a couple of end rotor blade carriers each carrying a series of blades forming an element of a section of the high-pressure stage, a disk-shaped rotor blade carrier subdivided at its periphery into a plurality of annular parallel flanges, central series of blades mounted on both faces of said carrier and forming the elements of the sections of the middle-pressure stage, series of blades mounted on both faces of the peripheral flanges and forming the elements of the sections of the low-pressure stage and a plurality of rods regularly spaced on the periphery of said end carriers for connecting together these latter and supporting and holding in position the annular intermediate carriers.
17. In a radial turbine, inner and outer rotors comprising disk shaped members each having a central series of blades for the high pressure stage, a peripheral series of blades for the low pressure stage and an intermediate connecting portion having an annular restricted zone to provide for the necessary flexibility between the central and peripheral portions.
- In testimony whereof I have affixed my signature.

ALFRED BONOM.
